UNITED STATES PATENT OFFICE.

JOHN G. BROMAN, OF CHICAGO, ILLINOIS.

STEAM-BOILER.

1,165,064.

Specification of Letters Patent. Patented Dec. 21, 1915.

Application filed February 14, 1914. Serial No. 818,784.

To all whom it may concern:

Be it known that I, JOHN G. BROMAN, a citizen of the United States, and a resident of the city of Chicago, in the county of Cook 5 and State of Illinois, have invented certain new and useful Improvements in Steam-Boilers; and I do hereby declare that the following is a full, clear, and exact description of the same, reference being had to the accompanying drawings, and to the numerals of reference marked thereon, which form a part of this specification.

Experiment has shown that the efficiency of a boiler is directly dependent upon the 15 amount or rate of circulation of the water therethrough. In the older types of boilers the water was permitted to remain practically quiescent during heating, but, in the modern type, great care is exercised in the 20 construction to insure a rapid circulation of the water, the production of a thermo-siphon serving to promote the circulation. However, in small boilers of high horse power where the water is caused to circulate 25 rapidly, the ebullition of steam is more or less violent, and, owing to the movement of the water throughout the boiler, foaming and priming have formed serious difficulties. In the older types of boiler where the water 30 remains at rest while being heated, the disengagement of the steam from the water is not generally attended by any violent disturbance of the water, and with a reasonably large steam space, practically dry steam 35 is easily obtained.

This invention relates to a boiler equipped with baffle surfaces so disposed as to form compartments effecting a partial separation of the water of different temperatures to 40 preserve as near as possible a heating cycle. Furthermore, the steam obtained is free from entrained moisture, and the water is made to circulate rapidly through the boiler. Mechanism is also provided for collecting 45 impurities from the surface of the water, the rapid movement of the water facilitating the operation.

It is an object of this invention to construct a boiler wherein the steam drum is 50 partitioned to effect separation of the water of different temperatures, and further providing a chamber for the disengagement of the steam, the steam then passing into the main steam space in the steam drum, and in 55 its passage being freed from entrained water.

It is also an object of this invention to construct a boiler in which a rapid circulation of the water takes place, due to the different temperatures thereof, and in which the 60 rapid ebullition of steam is confined to water contained in a partitioned space communicating with the main steam space of the boiler.

It is also an object of this invention to 65 construct a boiler wherein means are provided for deflecting the circulating water in a manner to prevent undue disturbance thereof and whereby, owing to the movement of the water impurities floating on 70 the surface may be collected or skimmed off at one point and blown out of the boiler from time to time.

It is also an important object of this in- 75 vention to construct a boiler in which the portion of the water, from which the greatest amount of the steam is evolved, is confined in one part of the boiler, but is permitted to pass into other portions of the 80 boiler from time to time without violent disturbance, so that practically dry steam may be obtained and foaming is prevented.

It is also an object of this invention to 85 provide a boiler equipped with baffle plates adapted to confine that portion of the water from which the steam is being evolved within a certain part of the boiler, and with other baffle plates to direct the evolved steam into the main steam space of the boiler in a manner to receive the steam from entrained 90 water, thus preventing disturbance of the entire quantity of water in the boiler and insuring a rapid circulation thereof.

It is also an object of this invention to 95 construct a boiler wherein only a small quantity of water is disturbed by the ebullition of steam and the main quantity of water is caused to circulate without foaming or priming, and in which the evolved steam passes over the relatively quiet cir- 100 culating water freed from entrained par- ticles of moisture.

It is also an object of this invention to 105 apply the principle involved in my device with very slight modification to either ver- 110 tical water tube boilers or to the familiar B. and W. type, having inclined tubes.

It is also an important object of my in- 115 vention to construct the mechanism which controls the direction of flow of the water and steam, of an adjustable nature whereby the mechanism may be changed to operate

properly for different water levels or for furnaces of different heating capacities.

It is furthermore an object of my invention to construct mechanism adaptable to boilers whereby the water from which the steam is disengaged may be confined temporarily in one portion of the steam drum and with adjustable means for deflecting the evolved steam into the main steam space, thereby freeing the steam from entrained particles of moisture; and with other adjustable deflecting means acting to direct the flow of the water from the steam drum of the boiler obviating disturbance of the water, and at the same time allowing the surface water to move therewith carrying the floating impurities.

It is finally an object of this invention to construct a boiler wherein the various portions of the circulating water are temporarily maintained in different parts of the boiler, but in communication with one another, so that turbulence is avoided and circulation of the water through the boiler augmented.

The invention (in a preferred form) is illustrated in the drawings and hereinafter more fully described.

In the drawings: Figure 1 is a side elevation partly broken away and partly in section, illustrating a B. and W. type of boiler embodying the principles of my invention. Fig. 2 is an enlarged detail sectional view taken through the forward end of the steam drum. Fig. 3 is a section on line 3—3 of Fig. 2. Fig. 4 is a central longitudinal vertical section with parts in elevation of a vertical water tube boiler embodying the principles of my invention. Fig. 5 is a section on line 5—5 of Fig. 4. Fig. 6 is a vertical longitudinal section through the rear of the steam drum. Fig. 7 is a vertical section on line 6—6 of Fig. 6.

As shown in the drawings, referring to Fig. 1, the boiler setting is denoted by the reference numeral 1, and is provided with a fire door 2, an ash door 3, and a grate 4. A flue passage 5, is provided in the rear wall of the setting for connection to the stack, and, a slight distance above the floor level, a soot door 6 is also mounted in said rear wall. Supported in the setting is a steam drum 7, and mounted below the same in inclined position are a plurality of water tubes 8, connected at their lower ends in a rear header 9, and at their upper ends in a front header 10, each of said headers communicating in the steam drum 7. A bridge wall 11, extends transversely of the setting at the rear of the grate 4, and built over said bridge wall and supporting said water tubes is a baffle wall 12. Another wall 13, arches transversely across the setting from the side walls thereof and, together with a wall 14, through which the tubes extend, affords

another baffle for the products of combustion. An opening is formed in the steam drum at the point indicated by the reference numeral 15, to admit attachment of a safety valve thereto, and a steam nozzle 16 is also secured in said drum, whereby a pipe lead to the main header of a battery of boilers may be connected. An angle iron 17 is secured circumferentially around the interior of the steam drum, and secured thereto in the lower half of the drum is a semi-circular partition 18, which is turned or curled along its upper edge as indicated by the reference numeral 19. A downwardly directed curved baffle plate 20, is rigidly secured forwardly of said angle iron ring 17, on the under side of the top wall of the steam drum, and another curved baffle plate 21, is pivotally mounted upon a rod 22, which extends transversely across said angle iron ring at the end of said baffle plate 20. The outer end of the baffle plate 21, is supported by means of the links 23, and 24, respectively, which are each apertured at a plurality of points and adjustably connected by a connecting bolt 25, to permit extension of the link connection. Said link 23, is pivotally connected to the baffle plate 21, and said link 24, is likewise pivotally connected to the top wall of the steam drum. Another baffle plate 26, is fastened to the lower wall of the steam drum near the rear end thereof, and is curved to project over the point at which the rear header communicates in said drum. Directly back of said baffle plate a blow-off connection 27, is connected in the bottom of the steam drum, so that impurities floating on the surface of the water will pass over the baffle plate and collect at the rear of the drum where they may settle, and be blown off from time to time.

In the construction illustrated in Figs. 4 and 5, the principle of operation is exactly the same. However, in this case an upright or vertical water tube boiler is shown. The boiler setting is denoted by the reference numeral 28, and is provided, as usual, with a grate 29, and a flue duct or passage to the stack 30. Supported on the upper end of the setting is a steam drum 31, and at the lower end a water drum 32, is mounted, said steam drum and water drum being connected by a plurality of vertical water tubes 33. A baffle wall 34, extends from the water drum upwardly to a point a short distance below the steam drum, so that the products of combustion, as shown by the arrows, leaving the grate 29, pass upwardly around certain of the water tubes and downwardly around the others thereof and out at the flue duct 30. A partition 35, extends transversely across the crown sheet 36, of the steam drum, and is secured to the side walls thereof, said partition inclining toward the front of the steam drum, and provided with

a curled or turned edge 37, along its upper margin. A curved baffle plate 38, is pivotally mounted on the front wall of the steam drum, and held in position by means of links 39, and 40, respectively, adjustably connected to one another in the same manner as the links 23, and 24, already referred to in the prior construction. A stationary outwardly curved baffle plate 41, is secured 10 on the front wall of the steam drum, and its upper edge extends to a point slightly above the pivotal connection for the adjustable baffle 38.

The operation is as follows: Referring 15 first to Figs. 1 to 3 inclusive, it is to be noted that the normal water level in the steam drum is slightly below the top of the curved portion 19, of the partition 18, and that furthermore the front header 10, projects 20 upwardly a short distance through the bottom of the steam drum. When a fire is upon the grate 4, the products of combustion first sweep upwardly around the forward ends 25 of the water tubes, thence around and downwardly between the baffle walls 12, and 14, respectively, and finally upwardly behind the baffle walls 13, and 14, and out through the flue passage 5.

Owing to the inclination of the water 30 tubes, a thermosiphon is set up and the water flows therethrough in the direction of the arrows. Of course, the forward ends of the tubes being subjected to the greatest heat from the furnace, and the water flowing 35 thereinto having previously been heated at the lower ends of said tubes, a rapid ebullition of steam and flow of water takes place through the end of the front header projecting into the steam drum. Owing to the 40 disengagement of the steam, the water contained in the steam drum forwardly of the partition 18, is in a constant state of disturbance, but the disturbance is not communicated to the main quantity of water in 45 the steam drum on the rear side of the partition 18. From time to time, as the level of the water on the forward side of the partition rises, the water spills over the curved upper edge thereof, and then flows rearwardly with the main quantity of water in 50 the steam drum downwardly into the rear header 9, and again upwardly through the water tubes.

The steam evolved at the forward end of 55 the steam drum, owing to the turbulent state of the water therein, carries more or less moisture, and accordingly the baffles 20 and 21, are provided, which, as the steam flows into the main steam space in the drum, 60 direct the same downwardly, the change in direction of flow thereof serving to throw out the particles of moisture. Owing to the relatively quiescent state of the circulating water in the main portion of the 65 steam drum, the steam contained in the

steam space thereabove is maintained in an exceedingly dry state.

There is, of course, a constant circulation of the water in the steam drum from the front to the rear thereof, and of course floating impurities are carried with the water. As the circulating water strikes the baffle 26, it is directed downwardly into the rear holder 9, and, owing to the fact that the baffle 26, does not extend above the surface 75 of the water, the impurities by their own inertia are carried or skimmed thereover and then settle in the compartment behind the baffle, and are blown off from time to time, as desired, through the blow-off 27. 80

In the construction illustrated in Figs. 4, and 5, the principle of operation is identical with that already described. In this vertical type of boiler the steam is evolved in front of the partition 35, and as it flows 85 upwardly after its disengagement from the surface of the water, strikes the curved deflector 38, which re-directs the steam downwardly again on the rear side of the partition 35, the change in direction of flow 90 thereof serving to throw out the particles of entrained moisture, and the steam then passes upwardly into the steam space above the deflector 38, in an exceedingly dry state. The deflector 38, also serves to prevent 95 water foaming in the steam drum into the steam nozzle, which may be connected in at the point 42.

I am aware that details of construction may be varied through a wide range, and the particular way in which the baffle plates and partitions are mounted is immaterial, as obviously the principle involved may be gained by application of similar mechanisms. I therefore do not purpose limiting 100 the patent granted otherwise than necessitated by the prior art.

I claim as my invention:

1. In a boiler of the class described a steam drum, a compartment therein for the water from which most of the steam is evolved, a passage permitting flow of steam and water from said compartment into the main portion of the steam drum, means adapted to deflect the steam during said flow 110 to free the same of entrained water, and a baffle plate adapted to direct the water outwardly from the drum, insuring a constant circulation of the water without turbulence. 115

2. In a boiler of the class described means temporarily confining the water from which most of the steam is evolved, means permitting flow of said confined water and evolved steam into a main portion of the boiler, and adjustable baffle plates disposed in the path 120 of the steam to deflect the same and disengage entrained water therefrom. 125

3. In a device of the class described the combination with the heating surfaces and the steam drum of a boiler, of a partition 130

therein adapted to prevent immediate intermingling of the water from the heating surfaces with the other water in the drum, a deflector disposed over said partition to direct the evolved steam downwardly to free the steam of entrained moisture, and means adjusting said deflector for different water levels.

4. In a device of the class described the combination with the steam drum of a boiler, of a partition therein adapted to confine the heated water in one portion of said steam drum while the steam is being evolved therefrom, said partition permitting an overflow of said water into the main portion of the steam drum when the level of the water in said confined portion rises, and baffle plates, certain ones disposed above the surface of the water to direct the flow of steam into the main portion of the steam drum, and another baffle plate to direct the flow of water from said steam drum.

5. In a device of the class described the combination with the heating surfaces and the steam drum of a boiler, of a baffle plate disposed below the water level in said steam drum to direct the circulating water in said drum toward the heating surfaces, another baffle disposed transversely of the steam drum to prevent the turbulent water flowing from the heating surfaces from mingling with the water in the main portion of the steam drum, and a deflector disposed above the water level in the steam drum to deflect the steam evolved from said turbulent water to free said steam of entrained moisture.

6. In a device of the class described a boiler comprising a steam drum, a main steam space, a main water space, means deflecting the circulating water from said water space to the heating surfaces of the boiler, a plate having a hooked upper edge located adjacent the drum intake, and a partitioned space formed by said plate adapted to receive the water from the heating surfaces to permit evolution of steam therefrom without transmitting the turbulence to the water in the main water space.

7. A boiler of the class described comprising a steam drum, a main steam space, a main water space, means deflecting the circulating water from said water space to the heating surfaces of the boiler, a partitioned space in said steam drum adapted to receive

the water from the heating surfaces to permit evolution of steam therefrom without transmitting the turbulence to the water in the main water space, and pivotally connected means for varying the direction of flow of water and steam into said main spaces.

8. In a device of the class described the combination with the heating surfaces and the steam drum of a boiler, of a partition therein adapted to prevent immediate intermingling of the water from the heating surfaces with the other water in the drum, an auxiliary chamber formed by said partition, an oblique baffle plate rigidly secured in the upper part of said chamber, an adjustable baffle plate pivotally connected to said oblique baffle plate extending into the main chamber of said drum to direct the evolved steam downwardly, and pivotally connected link extension members attached to said adjustable baffle plate and to the top wall of the steam drum to regulate the position of said adjustable baffle plate.

9. In a device of the class described the combination with a steam drum embracing an auxiliary chamber and a main chamber, of a plurality of baffle plates rigidly secured on the bottom of said drum one extending above the water surface, another terminating below the water surface, and a plurality of adjustable baffle plates above one of said lower baffle plates extending from said auxiliary chamber into said main chamber adapted to control the direction of flow of evolved steam into said main chamber.

10. In a device of the class described the combination with a steam drum, of a plurality of baffle plates rigidly secured to the bottom of said drum, a plurality of baffle plates attached at the top of said drum, a plurality of extension members connected between said upper baffle plates and the top of the drum, a compartment behind one of said lower baffle plates adapted to accumulate impurities, and means connected with said compartment for blowing off the impurities.

In testimony whereof I have hereunto subscribed my name in the presence of two subscribing witnesses.

JOHN G. BROMAN.
